UNITED STATES PATENT OFFICE.

ALBERT L. PARCELLE, OF BOSTON, ASSIGNOR TO A. B. COFFIN, OF WINCHESTER, ONSLOW GILMORE, OF STONEHAM, AND BENJAMIN A. FOWLER, OF STONEHAM, MASSACHUSETTS, TRUSTEES.

HAND-WHEEL FOR SEWING-MACHINES.

SPECIFICATION forming part of Letters Patent No. 247,398, dated September 20, 1881.

Application filed March 15, 1881. (No model.)

To all whom it may concern:

Be it known that I, ALBERT L. PARCELLE, of Boston, in the county of Suffolk and State of Massachusetts, have invented certain Improvements in Hand-Wheels for Sewing-Machines, of which the following is a specification.

This invention relates to sewing-machines in which the driving-pulley on the driving-shaft in the machine head or neck which operates the stitch-forming mechanism is provided with an enlarged offset periphery or hand-wheel for operating a bobbin-winder, and is adapted to be released, so as to move loosely upon the shaft, and thereby operate the bobbin-winder without operating the driving-shaft and the stitch-forming mechanism.

The invention has for its object to provide simple and effective means for enabling the operator, by a very slight movement of a screw-bolt, to make the pulley either fast or loose upon its shaft.

To this end the invention consists in the combination, with a loose pulley having an internal annular surface, of a shaft having radial guides, locking-arms movable in said guides and adapted to move endwise against the annular surface, and a wedge-bolt adapted to be moved longitudinally in a socket formed in the shaft and force the locking-arms outwardly against the annular surface, thereby making the pulley fast upon the shaft.

The invention also consists in the provision of a spring to automatically retract the locking-arms when the wedge-bolt is retracted, all of which I will now proceed to describe and claim.

Of the accompanying drawings, forming a part of this specification, Figure 1 represents a longitudinal section of a portion of the driving-shaft of a sewing-machine having a driving-pulley and hand-wheel and a clutch mechanism embodying my invention. Fig. 2 represents a section on the line $x-x$, Fig. 1.

The same letters of reference indicate the same parts in both figures.

In the drawings, a represents a portion of the head or neck of a sewing-machine.

b represents the rear end of the driving-shaft

which actuates the stitch-forming mechanism, 50 and is journaled in the neck a , as usual.

c represents the driving-pulley, which rotates the shaft b , and is connected by a belt to the main driving-wheel of the machine.

d represents the hand-wheel, which consists 55 of an enlarged periphery or rim offset from the pulley c , and rigidly attached to or forming an integral part of the latter. The pulley c is chambered out on one side to form an internal annular surface, c' .

d' d' represent guides or sockets radiating from the center of the shaft b toward the annular surface c' . The outer portions of said guides are preferably formed in a collar, b' , rigidly attached to the shaft b .

e e represent locking-arms located in the guides d' d' , and movable therein toward and from the surface c' . These arms are adapted to bear at their outer ends against the surface c' , and may be of any desired form, the T shape 70 shown in Fig. 2 being preferred, the outer side of the cross-piece being curved to fit the curvature of the surface c' .

f represents a wedge-bolt, which is located in a longitudinal socket, g , in the shaft b , and 75 is provided with a tapering or conical inner end interposed between the inner ends of the arms e e . The bolt f is threaded at its outer end and engaged with a correspondingly-threaded portion of the socket g , so that when the bolt 80 is rotated it is moved longitudinally. If the movement of the bolt is in one direction, its tapering end will act as a wedge and move or project the arms e outwardly, causing the heads of said arms to bear on the surfaces c' , and thus 85 locking the pulley upon the shaft. If the movement of the bolt is in the opposite direction, it releases the arms e and makes the pulley loose.

i represents a spring, connecting the arms 90 e e , and adapted to retract said arms and separate them from the surface c' when they are released.

j represents an enlarged head on the outer end of the wedge-bolt f , said head being at the 95 end of the shaft b , and constituting a handle for the operator to grasp in turning the bolt.

It will be seen that the locking-arms may be

moved to lock or release the pulley by a very slight rotary movement of the bolt *f*, and that when said arms are projected they are firmly held by the wedge-bolt, and constitute a strong 5 and efficient means for connecting the shaft and pulley.

Having thus described my invention, what I claim, and desire to secure by Letters Patent, is—

- 10 1. The loose pulley *e*, having an internal annular surface, *c'*, the shaft *b*, constructed with guides or sockets *d' d'*, and the arms *e e*, arranged in said guides, combined with the wedge-bolt *f*, arranged in a longitudinal threaded 15 socket in the shaft, and adapted to operate

the locking-arms *e e*, substantially as shown and described.

2. The combination of the chambered pulley *c*, spring-arms *e e*, arranged in suitable guides, *d' d'*, and the operating-bolt *f*, provided 20 with the head *j*, all constructed and arranged substantially as shown and described.

In testimony whereof I have signed my name to this specification, in the presence of two subscribing witnesses, this 24th day of February, 25 A. D. 1881.

ALBERT L. PARCELLE.
